UNITED STATES PATENT OFFICE.

OLIVER O. SCHWOB, OF MOUNDSVILLE, WEST VIRGINIA, ASSIGNOR TO J. A. SCHWOB CO., OF MOUNDSVILLE, WEST VIRGINIA.

SCYTHE AND POST FASTENING FOR GRAIN-CRADLES.

1,124,816.

Specification of Letters Patent.

Patented Jan. 12, 1915.

Application filed July 24, 1914. Serial No. 852,847.

To all whom it may concern:

Be it known that I, OLIVER O. SCHWOB, a citizen of the United States, residing at Moundsville, in the county of Marshall and State of West Virginia, have invented new and useful Improvements in Scythe and Post Fastenings for Grain-Cradles, of which the following is a specification.

The invention provides novel fastening means for securing a scythe and cradle to a snathe, in a manner to secure a rigid joint, to allow for lateral adjustment for variation in the length of the scythe or head to admit of the scythe being readily removed or replaced without requiring the use of tools other than a hammer to provide for quick assembling or separating of the parts, and which is simple and embodies comparatively few parts.

A further purpose of the invention is the provision of fastening means of the character hereinbefore stated, which insures a strong and durable joint and admits of the scythe being quickly removed for sharpening or other purpose and easily replaced without interfering with the fastening means between the head and snathe.

The invention consists of the novel features, details of construction and combination of parts, which hereinafter will be more particularly set forth, illustrated and claimed.

In the drawings hereto attached:—Figure 1 is a perspective view of a scythe and cradle provided with fastening means embodying the invention. Fig. 2 is a detail view showing more clearly the fastening means for securing the scythe and head to the snathe. Fig. 3 is a detail view of the end of the snathe and the plate attached thereto. Fig. 4 is a detail view in perspective of the end of the snathe to which the scythe and cradle are attached. Fig. 5 is a detail view of the plate. Fig. 6 is a detail section taken on line 6—6 of Fig. 3. Fig. 7 is a detail section taken on line 7—7 of Fig. 2.

Corresponding and like parts are referred to in the following description, and indicated in all the views of the drawing, by the same reference characters.

The numeral 1 designates a snathe or handle which may be of usual construction. The end of the snathe to which the scythe and cradle are attached is flattened upon one side as indicated at 2 and is rabbeted at

the sides of the flattened portion as indicated at 3. An opening 4 is formed in the flattened side 2 to receive the lateral projection 5 at the end of the tang 6 of the scythe 7.

A plate 8 is secured to the flattened side 2 of the snathe by fastenings 9, the latter passing through openings formed in the plate near opposite ends thereof. Flanges 10 are formed at opposite longitudinal edges of the plate 8 and are adapted to fit the rabbets 3, thereby preventing any lateral displacement or turning of the plate upon the snathe. The flanges 10 also stiffen and reinforce the plate. Intercommunicating openings 11 are formed in the plate 8 near the inner end thereof and come opposite the opening 4. The openings 11 are out of line longitudinally and laterally thereby making provision for adjustment of the scythe with reference to the snathe. A ferrule is formed at the outer end of the plate 8 which projects beyond the extremity of the snathe 1. The ferrule consists of a transverse opening 12 formed in the projecting end of the plate 8. The inner wall of the opening 12 is formed with a plurality of teeth 13 which engage one extremity of the post 14 so as to hold the same in the required position against slipping. The portion of the plate exterior to the opening 12 consists of a transverse bar 15 which is preferably made round in cross section to allow for relative angular adjustment of the cradle when adapting the same to the nature of the work or the convenience of the operator. The head consists of the post 14 and fingers 16, the post 14 being connected in the opening 12, and a plurality of braces 17 connecting the head with the snathe in the manner well understood.

The scythe 7 may be of usual construction and is secured to the plate 8 and snathe 1 by means of a band or ring 18 and key 19, the tang 6 passing through the band or ring 18 and the projection 5 at the extremity of the tang entering one of the openings 11. It will thus be understood that when the key 19 is removed the scythe may be easily disconnected from the snathe by sliding the band or ring 18 upon the snathe so as to clear the tang 6. The construction is such as to admit of the scythe being instantly removed or quickly replaced without disturbing the head or fastenings or interfering in any manner with the adjustment thereof.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the invention as claimed.

Having thus described the invention, what is claimed as new is:—

1. In combination, a snathe, a plate secured to a side of the snathe and having an end portion projecting beyond one end of said snathe, said projecting end having a transverse opening which is provided along one side with a plurality of teeth, a cradle

having its post connected with the opening of said plate and a scythe secured to the snathe.

25

2. In combination, a snathe having a flattened side near its lower end, and having an opposite edge portion of the flattened side rabbeted, a plate secured to the flattened side of the snathe with its end portion projecting beyond the snathe and having flanges at its longitudinal edges to enter the rabbets of the snathe, said projecting end of the plate having a transverse opening, a cradle having its post connected with the opening formed in the projecting end of the plate, and a scythe secured to the plate.

35

In testimony whereof I affix my signature in presence of two witnesses.

OLIVER O. SCHWOB.
